UNITED STATES PATENT OFFICE.

EUGEN HABERFELD, OF BERLIN-HALENSEE, GERMANY, ASSIGNOR TO LATHAM LITHO & PRINTING CO., OF NEW YORK, N. Y., A CORPORATION OF NEW YORK.

DEVICE FOR CREATING AN OPTICAL ILLUSION.

Application filed March 11, 1926. Serial No. 94,072.

My invention has for its object to produce a device for creating an optical illusion of a liquid continually travelling in one direction which I accomplish by applying a certain 5 amount of heat to a liquid container into which extends a narrow tube into and through which the liquid is forced by the heat applied to the container. The container is provided with a tubular extension into 10 which the liquid passes. As the liquid reaches a certain point in said tubular extension it has sufficiently cooled off so as to return along the wall of the tubular extension and through the narrow tube to the container, while other liquid passes through 15 said tubular extension in the opposite direction. If the tubular extension is made of glass or other transparent material, there is created the illusion of a continual flow of 20 liquid through the tubular extension, as the small amount of liquid returning to the container along the inner wall of the tubular extension does not become visible, except perhaps on very close examination. Such a 25 device may be used as an advertising device, to create, for instance, the illusion of a person continually sucking up a liquid through a "straw," but, of course, other uses for such a device will readily suggest them- 30 selves.

In describing my invention in greater detail, I have reference to the accompanying drawing, in which an embodiment of the invention has been illustrated, by way of example, Fig. 1 showing a woman at a "soda fountain" drinking from a glass through a "straw"; Fig. 2 is a sectional view, showing the arrangement of the glass and the "straw" and the source of heat; Fig. 3 is a longitudinal section through the container representing the "straw".

The face of a woman with a window in the background is pictorially presented on a large cardboard, supported in position in a 45 show-window or at any other suitable place by a wing 2 (Fig. 2). On a shelf 3 in front, there is placed a cup 4 which may be either opaque or translucent. Within said cup is disposed the liquid container 5, which in the 50 drawing, is shown bulb-shaped, but may of course, have any desired or convenient shape to suit the conditions. Into this container 5, adapted to hold a certain amount of liquid shown at 6 in Fig. 3 projects a narrow tube 7, the lower end of which is immersed into

the liquid 6. At the upper end of the container 5, where the narrow tube 7 terminates closing the container by a circular flange 8, the container is provided with a transparent tubular extension 9 which is considerably larger than the narrow tube 7 and which is sealed at its extremity as shown at 10 in Fig. 3. Below the bulb-shaped container 5 is disposed a small electric lamp 11 (Fig. 2) held in an ordinary lamp-socket 12 connected by wires 13 to some convenient source of electrical energy.

When the electric lamp 11 is connected, the heat radiated thereby heats the liquid in the bulb-shaped container 5 sufficiently to force the same up into the narrow tube 7, and as more and more liquid is thus forced through said tube, it enters the large tubular extension 9, rising therein to a certain height indicated at 14 in Fig. 2. The upward direction of flow of the liquid in the tubular extension 9 is indicated by the large arrow 15 in Fig. 3. After the liquid has risen to a certain height in said tubular extension 9, it cools off and slowly glides down along the inner wall of extension 9 and through the narrow tube 7 back into the container 5, this direction of flow of the liquid being indicated by the small arrows indicated at 16 and 17 in Fig. 3. Thus the illusion of a substantially uninterrupted upward flow of liquid in the tubular extension 9 is created, so that the casual observer in case of the illustrated example receives the impression of liquid being continually sucked up through the tube 9.

I claim as my invention:

1. The combination of a closed liquid container, a narrow tube extending into said container being immersed into the liquid therein, a tubular extension provided on said container and closed at its free end, a source of heat for heating the liquid in said container, and means for positioning said source of heat in proper relation to said container.

2. The combination of a closed liquid container, a narrow tube extending into said container being immersed into the liquid therein, a transparent tubular extension provided on said container and sealed at its free end, a source of heat for heating the liquid in said container and means for positioning said source of heat in proper relation to said container.

means for camouflaging said container and 20
source of heat.

5. The combination of a closed liquid container, a narrow tube extending into said container being immersed into the liquid therein, a transparent tubular extension provided on said container and sealed at its free end, a source of heat for heating the liquid in said container, means for maintaining said source of heat in proper position with respect to said container, and means for sealing said container and source of heat. 10

5. The combination of a closed liquid container, a narrow tube extending into said container and immersed into the liquid therein, a transparent tubular extension provided on said container and sealed at its free end, a source of heat for heating the liquid in said container, means for maintaining said source of heat in proper position with respect to said container, and translucent 15

5. The combination of a closed liquid container, a narrow tube extending into said container and immersed into the liquid therein, a transparent tubular extension provided on said container and sealed at its free end, a source of heat for heating the liquid in said container, means for maintaining said source of heat in proper position with respect to said container, and translucent 20

5. The combination of a closed liquid container, a narrow tube extending into said container and immersed into the liquid therein, a transparent tubular extension provided on said container representing a "straw" and sealed at its free end, an electric incandescent lamp for heating the liquid in said container, a translucent cup-shaped part concealing said container and said lamp, and a card-board with a face painted thereon, the free end of said tubular extension entering through a slot in said card-board made between the lips of the face painted thereon. 25

In testimony whereof I affix my signature.

EUGEN HABERFELD.
